SWITCH WITH PRESSURE FLUID ARC
EXTINGUISHING

André Latour, Grenoble, France

Application November 27, 1946, Serial No. 712,478
In France December 3, 1945

10 Claims. (Cl. 200—148)

1

This invention relates to electric circuit-breakers of the fluid blast types, wherein an arc formed upon separation of the switch contacts is extinguished by a blast of fluid directed across the arc gap.

Circuit-breakers of that kind are known, in which one of the arcing contacts is formed by a nozzle, which according to a further improvement of the prior art, is movable, the pressure fluid acting on said nozzle as on a piston, thus promoting or accelerating the separation of the cooperating arcing contacts.

An object of the present invention is to diminish the inertia of such a device, and to provide a movable contact member of very light construction having a central aperture, said contact member resting or being pressed in closed position of the circuit-breaker, on the coöperating contact, and being separated from said contact and pressed against a coöperating fixed part, preferably forming a nozzle, by the pressure fluid, thus forming, in open position, with said fixed part preferably a nozzle-like electrode.

Another object of this invention is to provide a movable contact-member as described hereabove, and constituted by an assembly of several parts in view to diminish the inertia of the movable parts.

A further object of this invention is to provide a movable contact member as described hereabove, the movement of which is promoted by a piston actuated by a pressure fluid and provided with means adapted to increase the shock-like action of the piston on the movable contact member.

Another object of this invention is to provide a piston, actuated by the pressure fluid, coaxial with the stationary contact member, and adapted so as to direct the pressure fluid to the arc gap, preferably giving to said fluid a centripetal blast direction.

A further object of this invention is to provide a piston, actuated by the pressure fluid, coaxial with the stationary contact member and shaped so as to exert a confining action on the arc gap as described in my copending applications Nos. 723,724 and 723,727, both filed January 23, 1947, which issued as Patents 2,494,661 on January 17, 1950, and 2,573,797, on November 6, 1951, respectively.

Other objects of my invention will be apparent from the following description of an embodiment of the invention with reference to the accompanying drawings.

In the drawings:

Figure 1 is a sectional view taken on the axis of the device;

Figure 2 is a fragmentary plan view of movable contact members;

Figure 3 is a fragmentary plan view of a dif-

2

ferent embodiment of the movable contact members;

Figure 4 is a fragmentary vertical section of a modification of the pressure fluid actuated means;

5 Figure 5 is a fragmentary vertical section of a modification of the contact members.

As illustrated in Figs. 1 and 2 the circuit-breaker is in its closed position, the path of the current being indicated by the broken line at the 10 left of Fig. 1, 1 designates the stationary contact member, 2 the movable contact member, 3 the current input terminal, 4 a spring clip providing the stationary contact of a series disconnecting switch, 5 a movable cylinder providing the 15 movable contact of said disconnecting switch. The whole mechanism is contained in a casing 22, to which the extinguishing means is supplied.

The circuit breaker is operated by a pressure fluid, such as compressed air whose path of flow 20 is indicated by the arrows F, F₁ and F₂, the arrows F₂ indicating the path of the pressure fluid stream extinguishing the arc.

The pressure fluid which follows the path F₁ actuates the piston 6 to which it imparts an 25 ascending movement. Secured to the top portion of piston 6 is a member 7, preferably made of some insulating material or insulated from the piston, which serves to lift the movable contact 2.

The movable contact 2 is preferably formed by 30 several substantially flat sector-shaped members forming together a central passage and enabled to rock about pivots, for instance about a metal rim 8 against which the flat contact members are pressed by springs 9 surrounding fixed bolts 10. Said springs are effective to reliably keep the 35 members in circuit closing position.

The operation of the device will be easily understood. The combined circuit-breaker and disconnecting switch is shown in Figure 1 in its 40 circuit-closing position. In order to break the circuit, a pressure fluid is forced along the path indicated by the arrows F. As the fluid flow arrives at the bottom of piston 6 it is divided into two flows that follow the paths indicated 45 by the arrows F₁ and F₂, respectively. The one which takes the way F₁, enters the space below the piston 6 and causes the same to slide upwards in the cylinder 11.

The member 7 urges the movable members 2 upwards and causes them to rock about the pivots determined by the metal rim 8 until the members 2 come into engagement with a stop 12, preferably in the form of a nozzle, which limits the displacement of the movable contacts 2.

55 At such time an arc is struck between the fixed contact 1 and the movable contact members 2. The air stream F₂ follows its path in its channel and is abruptly deflected by the bend between the portion 13 of the fixed contact 1, and the 60 now lifted member 7 thus creating a violent air

inrush directed at right angles to the arc. This centripetal blowing effect is supplemented by a longitudinal blowing action created by the resulting air streams which flow along the paths indicated by the arrows F''_2 and F''_2 .

The air stream F''_2 shifts the upper end of the arc from the movable contact members to the spark-arresters 14 as described in my copending application, Serial No. 723,725, filed January 23, 1947. By the joint action of the air jet and the electrodynamic forces tending to lengthen the arc, the end of the arc is caused to sweep in turn the active surface of each spark-arrester; at the same time the air stream F''_2 will blow the lower end of the arc downwards into the stationary contact 1. The arc is thus lengthened at the same time as it is squeezed concentrically, which results in the desired extinguishing effect.

At this moment the movable contact cylinder 5 of the disconnecting switch begins to move downwards by the action of an actuating device, not shown in the drawings, whereby the circuit through said cylinder and the contact spring clip 4 is interrupted. Disconnection is thus obtained, the flow of pressure fluid is stopped, and the movable contact members 2 are returned by the springs 9 to their initial position, which is also their closing position.

In the meantime the fluid flowing along the path F''_2 , which has been heated and ionized by contact with the arc, is discharged and cooled by the muffler 15.

The circuit-breaking process may be aided by the interposition of a resistance 16 between the contact members 1 and 2.

In order to re-establish the circuit, it is only necessary to impart an ascending motion to the movable cylinder 5 of the disconnecting switch so as to re-establish connection through cylinder 5 and spring clip 4 in the disconnecting switch, connected in series with the circuit-breaker.

Figure 3 shows a modification of the invention as described above wherein the set of the substantially triangular movable contact members of Figure 2 is replaced by a pair of elongated movable members which are substantially rectangular in shape. Thereby, the device is reduced in width and can be accommodated more easily within a limited space. Said elongated movable members are pivotally mounted on the pivots 8, and are pressed against the stationary contact member 1, by means of springs not shown in the drawings, surrounding the fixed bolts 10. The two movable members provide, at their center, a circular aperture coaxial with the aperture of the hollow stationary contact member 1.

It is to be understood that this invention extends to contact members of any desired shape which will operate similarly to the ones described here above.

Figure 4 shows a modification of the invention whose purpose is to delay the effective motion of the piston 6 so that the contacts will not open before a sufficient fluid pressure is established.

With this end in view, according to the arrangement shown in Figure 4, the displacement of the piston 6 is effective in two parts, viz.: an initial movement which has no effect upon the movable contact member 2, and in the course of which the piston 6 is accelerated after it has left its initial position and thereafter a final high-speed movement effective to lift the movable contact member 2.

For that purpose it may be contemplated to lengthen the idle stroke of the piston in such a

manner that the piston 6 has a comparatively high speed when the insulating member 7 engages the movable contact parts 2. Alternatively, according to the arrangement shown in Figure 4, one or several additional ducts 17 are provided through which pressure fluid is admitted. Thus, before any pressure fluid is admitted, the piston remains seated on the bottom of its cylinder by the effect of gravity or the action of resetting means, not shown in the drawings. In this position of the piston, pressure fluid can flow into the space below the piston only by leakage, or through one or several narrow apertures 21, thus causing the piston to move slowly upwards until the apertures of one or more ducts 17 of comparatively wide cross-section are uncovered through which pressure fluid rushes into the space under the piston, causing the latter to move upwards at highly increased speed.

Figure 5 shows a further modification of the device described hereinbefore in which a more reliable engagement between the movable contact members 2 and the stationary contact member 1 is obtained.

It is well known that a repulsive force is set up between currents flowing in opposite directions through a pair of adjacent leads which is directly proportional to the intensity of the current and inversely proportional to the distance bewteen the leads.

In the embodiment shown in Figure 1, a repulsive force tends to move the movable contact members 2 away from the stationary contact member 1 so that, in spite of the pressure exerted by the springs 9, sparks might be expected to strike between the contacts and to damage the same. In order to preclude this occurrence, according to Figure 5, a loop in the circuit is provided, the repulsive force in said loop pressing the movable contact parts against the stationary contact. The movable contact members 2 are provided with a heel 18 to which the current is applied through a flexible conductor 19 connected at 20 to the input terminal 3. The metal rim 8 is replaced by an insulating rim 8', so that the current is compelled to flow through the conductor 19. Thus, a force is exerted upon the heels 18 which tends to move them away from 20. The effect of this force is to counteract the force which urges the contacts away from each other, so that the movable contact members 2 remain pressed against the stationary contact 1 by the action of the springs 9, and that possible deterioration of the contact members by sparks is avoided.

It is to be understood that various modifications may be made in the details of the afore-described devices without thereby departing from the scope of the invention and that in particular 60 modifications may be made in the shape of the piston and the contact members as well as in the relative position of the parts.

I claim:

1. A circuit breaker of the fluid blast type 65 comprising in combination, a stationary contact member; a substantially flat movable contact member; means for resiliently pressing in circuit-closing position said movable contact member with one of its flat faces against said stationary contact member; a stationary part arranged with respect to said substantially flat movable contact member so as to form a stop limiting the opening movement of said movable contact member; said stationary part, said stationary contact member and said movable contact member being

shaped so as to provide in any position of said movable contact member a passageway for the escape of the products of arcing; a piston actuated by fluid pressure for causing separation of said movable contact member from said stationary contact member and for pressing said movable contact member in circuit-opening position against said stationary part; and means for causing an arc-extinguishing blast between said contact members.

2. A circuit breaker of the fluid blast type comprising in combination, a stationary contact member; a substantially flat movable contact member; means for resiliently pressing in circuit-closing position said movable contact member with one of its flat faces against said stationary contact member; a nozzle-shaped stationary part arranged with respect to said substantially flat movable contact member so as to form a stop limiting the opening movement of said movable contact member; said stationary part, said stationary contact member and said movable contact member being shaped so as to provide in any position of said movable contact member a passageway for the escape of the products of arcing; a piston actuated by fluid pressure for causing separation of said movable contact member from said stationary contact member and for pressing said movable contact member in circuit-opening position against said stationary part; and means for causing an arc-extinguishing blast between said contact members.

3. A circuit breaker as claimed in claim 1, said movable contact member including a plurality of substantially flat members and a support for pivotally mounting each of said flat members.

4. A circuit breaker as claimed in claim 1, said movable contact member including a plurality of substantially flat sector-shaped members forming with their smaller sides a passageway for the escape of products of arcing; and a support for pivotally mounting each of said flat sector-shaped members.

5. A circuit breaker of the fluid blast type comprising in combination, a stationary contact member; a substantially flat movable contact member; means for resiliently pressing in circuit-closing position said movable contact member with one of its flat faces against said stationary contact member; a stationary part arranged with respect to said substantially flat movable contact member so as to form a stop limiting the opening movement of said movable contact member; said stationary part, said stationary contact member and said movable contact member being shaped so as to provide in any position of said movable contact member a passageway for the escape of the products of arcing; a piston abutting against said movable contact member; means for moving said piston by fluid pressure so as to cause separation of said movable contact member from said stationary contact member and to press said movable contact member against said stationary part; and means for causing an arc-extinguishing blast between said contacts.

6. A circuit breaker of the fluid blast type comprising in combination, a stationary contact member; a substantially flat movable contact member; means for resiliently pressing in circuit-closing position said movable contact member with one of its flat faces against said stationary contact member; a stationary part arranged with respect to said substantially flat movable contact member so as to form a stop limiting the opening movement of said movable contact member; said

stationary part and said movable contact member being shaped so as to provide a passageway for the escape of the products of arcing; a hollow piston surrounding said stationary contact member and abutting against said movable contact member, said movable contact member being shaped so as to provide a passageway coaxial with said piston; means for moving said piston by fluid pressure so as to cause separation of said movable contact member from said stationary contact member and to press said movable contact member against said stationary part; and means for causing an arc-extinguishing blast between said contacts.

7. A circuit breaker of the fluid blast type comprising in combination, a stationary contact member; a substantially flat movable contact member; means for resiliently pressing in circuit-closing position said movable contact member with one of its flat faces against said stationary contact member; a stationary part arranged with respect to said substantially flat movable contact member so as to form a stop limiting the opening movement of said movable contact member; said stationary part and said movable contact member being shaped so as to provide a passageway for the escape of the products of arcing; a hollow piston surrounding said stationary contact member and abutting against said movable contact member, said movable contact member being shaped so as to provide a passageway coaxial with said piston, said piston being shaped so as to provide a guiding passageway for the blast fluid; means for moving said piston by fluid pressure so as to cause separation of said movable contact member from said stationary contact member and to press said movable contact member against said stationary part; and means for causing an arc-extinguishing blast between said contacts.

8. A circuit breaker of the fluid blast type comprising in combination, a stationary contact member; a substantially flat movable contact member; means for resiliently pressing in circuit-closing position said movable contact member with one of its flat faces against said stationary contact member; a stationary part arranged with respect to said substantially flat movable contact member so as to form a stop limiting the opening movement of said movable contact member; said stationary part and said movable contact member being shaped so as to provide a passageway for the escape of the products of arcing; a hollow piston surrounding said stationary contact member and abutting against said movable contact member, said movable contact member being shaped so as to provide a passageway coaxial with said piston, said piston being shaped so as to provide a guiding passageway for the blast fluid in centripetal direction; means for moving said piston by fluid pressure so as to cause separation of said movable contact member from said stationary contact member and to press said movable contact member against said stationary part; and means for causing an arc-extinguishing blast between said contacts.

9. A circuit breaker as claimed in claim 6; said means for moving said piston including ducts of different cross-section for the admittance of fluid; said ducts of greater cross-section being obstructed by said piston in the initial part of the contact-opening movement of said piston.

10. A circuit breaker of the fluid blast type comprising in combination, a stationary contact member; a substantially flat movable contact

member; means for resiliently pressing in circuit-closing position said movable contact member with one of its flat faces against said stationary contact member; a stationary part arranged with respect to said substantially flat movable contact member so as to form a stop limiting the opening movement of said movable contact member; said stationary part and said movable contact member being shaped so as to provide a passageway for the escape of the products of arcing; a bell-shaped piston surrounding said stationary contact member and abutting against said movable contact member, said movable contact member being shaped so as to provide a passageway coaxial with said piston; means for moving said piston by fluid pressure so as to cause separation of said movable contact member from said stationary contact member and to press said movable contact member against said stationary part;

and means for causing an arc-extinguishing blast between said contacts.
